(57) **CLAIM**

The ornamental design for a frame for a VR headset, as shown and described.

DESCRIPTION

FIG. 1 is a perspective view of a frame for a VR headset showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view of the frame for a VR headset where the frame for a VR headset is in a configuration of use.

The broken lines in the drawings depict portions of the frame for a VR headset that form no part of the claimed design. The broken lines in FIG. 10 depict environment of the frame for a VR headset and forms no part of the claimed design.

1 Claim, 10 Drawing Sheets
